UNITED STATES PATENT OFFICE.

ALFRED A. SPADONE, OF NEW YORK, N. Y.

DESIGN FOR TILING.

SPECIFICATION forming part of Design No. 36,761, dated January 26, 1904.

Application filed January 2, 1904. Serial No. 187,600. Term of patent 14 years.

To all whom it may concern:

Be it known that I, ALFRED A. SPADONE, a citizen of the United States, residing in the borough of Manhattan, city, county, and State of New York, have invented a new, original, and ornamental Design for Tiling, of which the following is a specification.

The accompanying drawing is a face view of tiling, showing my new design.

I claim as my invention and desire to secure by Letters Patent—

The new, original and ornamental design for tiling as shown.

In testimony whereof I have signed my name to this specification in the presence of two subscribing witnesses.

ALFRED A. SPADONE.
